PHONOGRAPH RESET AND EXTERIOR LATCH MECHANISM

Theodore R. Duncan, North Hollywood, Calif., assignor
to Mattel Incorporated
Filed Apr. 13, 1959, Ser. No. 805,754
3 Claims. (Cl. 274—2)

This invention has to do generally with toy or miniature phonographs embodying a repeat or reset mechanism of the type set forth in my co-pending application entitled "Phonograph Repeat Mechanism," Serial No. 360,984, and more particularly to a release mechanism associated with the reset means for operating a catch or the like.

In my above referred to application for patent I show a reset mechanism for a phonograph wherein a reset means of a type embodying a lever pivotally mounted upon the phonograph record is utilized for returning the tone arm from the end of the record playing groove to the beginning thereof. An object of the present invention is to provide a novel means utilizing the reset means of the above referred to application for the purpose of actuating or releasing a catch or lever operably mounted on the phonograph and designed to releasably hold, or to be operably associated with another mechanism.

By way of example the phonograph unit may be incorporated in a toy of the jack-in-the-box type and used for releasing the cover of the box.

A further object is to provide a novel assembly in which a phonograph unit including a reset mechanism and a pivotally mounted catch or lever are embodied in a single merchandisable unit adapted for installation in a toy or other device for controlling some movable element of such device.

A further object is to provide a simple, durable fool-proof means of the type indicated which is cheap to manufacture. These and other objects will be apparent from the drawing and the following description. Referring to the drawing:

FIG. 1 is an elevational view, partly in section, showing a jack-in-the-box type of toy in which the invention is installed;

FIG. 2 is an enlarged fragmentary sectional view on line 2—2 of FIG. 1 with parts broken away;

FIG. 3 is a fragmentary view similar to FIG. 2, but showing the parts in a different position;

FIG. 4 is a view similar to FIG. 3 but showing the parts in a farther advanced position;

FIG. 5 is a sectional view on line 5—5 of FIG. 2;

FIG. 6 is a sectional view on line 6—6 of FIG. 2.

More particularly describing the invention, in FIG. 1 I show a toy 11 commonly termed a jack-in-the-box, the toy having a box-like casing or housing 12 with a lid or cover 13 hingedly mounted at 14 and movable from the closed position in which it is shown in full lines to the open position shown in broken lines. The cover may include a spring associated with the hinge 14 for yieldably urging the cover to open position, although this is not essential since in such devices the toy, FIGURE 15, is usually resilient or provided with an internal spring so that it must be compressed into the position shown and thus when the cover is closed it pushes upwardly against the cover tending to open it.

In order to releasably retain the cover closed it is provided with a bracket 16 having an eye portion 17 which is engaged by a latch member 18 forming part of the invention.

Mounted inside the casing 12 I show a miniature phonograph unit designated generally by 20. This includes a casing having opposed walls 21 and 22 connected by a side wall 23. Within the casing is a sound pickup arm 24 pivoted at 25, the arm being generally

2

L-shaped as viewed in plan and having a main section 26 and a laterally extending section 27 which terminates in a button or bearing surface 28 adapted to ride against the inner surface of wall 22. The arm carries a needle 28 for engaging the sound groove 30 of a record 32. The latter is fixedly secured to a spindle 34 which is journaled in the wall 21 and is formed as a crank 35 externally of the casing 12 with a handle portion having a rotatable sleeve 36.

10 The reset mechanism, which is substantially the same as that set forth in my co-pending application Serial No. 360,984, comprises a spring biased lever 40 having a base 41 apertured at its end to receive a mounting pin or rivet 42 carried by the record disk 32. Lever 40 is stepped at 43 and is provided with a needle engaging portion 44 disposed in a plane above portion 41 and such that its longitudinal axis forms an acute angle with the longitudinal axis of the portion 41. The portion 44 is characterized by a convexly arcuate forward edge 55 with a recessed edge portion or interruption 56 for engagement and reception of the needle of the sound pickup. Lever 40 is yieldably urged to a normal position of engagement of the end of portion 44 with the record spindle 34 by a wire spring 48 having legs 49 and 50 and 15 one or more turns 52 around the mounting pin 42. Leg 50 bears against the record spindle while the other leg bears against the stepped portion 43 of the lever being received in a recess 43' thereof.

On the pickup arm I provide a depending inclined tab 30 58 between the needle and the pivoted end of the arm. This provides an inclined cam face 59 which is first engaged by lever 40 in the operation of the device for the purpose of raising the tone arm and needle prior to the returning of the tone arm to the play-beginning position.

35 The latch member 18 comprises a piece of sheet metal formed to provide a mounting section 61 which is pivotally secured to the wall 21 of the phonograph by a rivet 62. A central portion 63 extends at right angles or normal to the mounting section and as a continuation of a portion of one edge thereof and includes a tongue section 64 which projects through an opening 65 in the wall 23 of the phonograph. Extending from the opposite edge of the central section 63 is a hook section 66 formed to lie generally parallel with section 61 and to provide an upwardly projecting hook 68 which releasably engages the eye section 17 of the bracket 16 on the cover 13 of the jack-in-the-box housing.

40 The latch member 18 is yieldably urged to upright position in which it is shown in FIGS. 1 and 2 by a spring 70 having a central portion 70' which extends about seven-eighths of a turn around the rivet 62 and has a leg 71 which bears against a mounting ear 72 of the casing and a leg 73 which bears against the central section 63 of member 18, all portions of the spring being 45 in a common plane. The portion of the spring about the rivet 62 serves in place of a washer to space the section 61 of the latch member from the side of the case.

45 In order to utilize the reset lever and pickup arm as a means of operating the latch member 18 which releasably holds the cover 13 of the box 12 I provide a series of slight protuberances or projections 60 spaced along the arcuate edge 55 of the lever. In place of these, ratchet-like teeth may be employed or any other means of a nature such that, as the reset lever is pivoted, it will engage the edge 64' of tongue section 64 of latch member 18 and pivot the same.

50 In the operation of the device, when the tone arm has traversed the record groove 30 and moved inwardly of the playing area, the lever means 40 first lifts the pickup arm as shown in FIG. 5 and subsequently engages the needle thereof in the recessed edge portion or interruption 56. As the record further rotates from such position the

reset lever pivots outwardly as shown in FIG. 3 to carry the tone arm with it to the outer portion of the record. As the reset lever moves outwardly the roughened edge portion of the section 44 engages the inner end or edge of the tongue 64 of latch 18 and subsequently pivots this lever against the action of its spring 70 out of engagement with the eye 17 of the bracket 16. Further movement of the record releases the needle and tone arm from the reset means and finally the latch 18 is released to return to its original position.

Although I have illustrated and described a preferred form of my invention, I contemplate that various changes and modifications can be made therein without departing from the invention, the scope of which is indicated by the following claims.

I claim:

1. In combination, a phonograph including a record disc and a sound pick-up arm, reset means for the pick-up arm for returning the pick-up arm to the play starting position, latch means positioned to be actuatable by the reset mechanism upon operation of the latter, a casing

having a cover having said phonograph within it, and means responsive to operation of the latch means to release the cover for automatically opening the cover at a predetermined point in the operation of the reset means.

- 5 2. A combination as in claim 1 including a jack-in-the box in the casing controlled by the said cover.
3. In combination, a phonograph including a record disc and a sound pick-up arm, said pick-up arm having starting and ending positions, a casing having a cover 10 having said phonograph within it, latch means positioned to be actuatable by the phonograph controlling the said cover, a jack-in-the box within the said casing and means whereby at a predetermined point in the playing of a record the phonograph operates the latch means to release the cover and expose the jack-in-the box.
